UNITED STATES PATENT OFFICE.

B. JAY ANTRIM, OF PHILADELPHIA, PENNSYLVANIA.

FIRE-ALARM.

SPECIFICATION forming part of Letters Patent No. 268,597, dated December 5, 1882.

Application filed August 3, 1882. (No model.)

To all whom it may concern:

Be it known that I, B. JAY ANTRIM, a citizen of the United States, residing in the city and county of Philadelphia, State of Pennsylvania, have invented a new and useful Improvement in Fire and Burglar Alarms, which improvement is fully set forth in the following specification and accompanying drawings, in which—

10 Figure 1 is a top or plan view of the alarm embodying my invention. Fig. 2 is a longitudinal vertical section thereof in line *x* *x*, Fig. 1. Fig. 3 is a transverse vertical section thereof in line *y* *y*, Fig. 2. Fig. 4 is a view of a modification of a portion thereof.

15 Similar letters of reference indicate corresponding parts in the several figures.

My invention consists of an automatically-operated fire and burglar alarm, the construction and operation being hereinafter fully set forth.

20 Referring to the drawings, A represents a holder for fire-crackers, cartridges, or other explosives, A', which is formed of sections *a a*, hinged or otherwise connected and channeled, as on their inner faces, forming barrels B to receive said explosives.

25 C represents spring-pressed plungers or pistons, which are fitted within the barrels B at the outer ends thereof, so as to be discharged by the explosive in said barrel. Within the holder is also a channel, D, extending at a right angle to the barrels B, and communicating with said barrels by means of ducts *b*, formed in the holder. In the walls of the holder are vents *c*, which communicate with the barrels at places above or below the plungers C, so that when the plungers are in their normal position they close the vents, as shown 30 in Fig. 3.

35 Formed with or secured to the holder A is a shelf, E, which sustains or guides the outer ends of the plungers C, and is formed with a series of notches, *d*, for supporting a series of bobs or weights, F, whose necks are adapted to enter said notches, whereby the weights are retained in position, it being noticed that the notches coincide with the barrels B, and consequently with the plungers C, whereby when 40 the latter are driven outwardly they are caused

to strike the weights F and force them from the shelf E. The weights F may be connected with alarm mechanisms in different apartments by means of cords or wires *e*; or the holder may be so disposed that said weights may drop on the floor of the apartment in which the holder is located, or be connected with weights which may be raised or lowered in other rooms, the object in all cases being that the displacement of the weights will cause alarms.

45 In the channel D is placed a fuse, G, which communicates with the explosives A' by means of the ducts *b*, powder or fulminate, if desired, being placed in said channel to insure the action of said fuse. The fuse is so placed that in the event of fire it will be ignited, or another burglar or fire alarm so disposed that when the latter is operated it will strike a match in proximity to the fuse, so as to ignite the latter. I may also employ acid or other 50 material of a kind which, when liberated, will cause ignition of the fuse, said material being directed against the fuse by the action of some other alarm, or the hand of a party in charge of the alarm, the latter causing alarms to be 55 sounded in different apartments. When the fuse burns and reaches the crackers, cartridges, &c., the latter are discharged, thus impelling the plungers from the barrels and forcing the weights from their seats on the shelf E, thus 60 sounding an alarm, as has been stated. As soon as a vent, *c*, is uncovered by the operated plunger the gas of the explosive escapes through the said vent, and the spring C' then restores 65 the plunger to its normal position.

65 The holder A, being in section, may be opened to remove the discharged explosive and apply a fresh one in lieu thereof, and in order to hold the sections firmly together for a subsequent operation I employ screw-clamps H, which embrace the ends or sides of the sections or projections thereon, and reliably connect the sections as one.

70 It is evident that the discharge of the explosive is also utilized as an alarm in addition to that created by the falling of the weights, thus providing a double alarm.

75 In Fig. 4 the vent *c* is shown in the piston, which is made partly hollow, so that said vent may answer its purpose. The springs C' op- 80

erate to replace the pistons in their original position after firing.

Having thus described my invention, what I claim as new, and desire to secure by Letters Patent, is—

1. In an automatically-operated fire and burglar alarm, a barrel containing explosive material, in combination with a plunger or piston also within said barrel, a weight supported in position to be dislodged by the outward movement of said piston, and a cord extending from said weight to a distant signal, which is operated by the falling of said weight, substantially as set forth.
2. In an alarm, a barrel for an explosive, a plunger provided with a vent and a restoring spring for the plunger, combined and operating substantially as and for the purpose set forth.
3. In an alarm, a barrel for an explosive, in

combination with a plunger in said barrel, a weight arranged to be dislodged by the outward movement of said plunger, and a spring whereby said plunger is replaced, substantially as set forth.

4. The holder consisting of the two hinged plates, *a a*, correspondingly channeled to form a series of barrels for explosives, in combination with a series of plungers fitting in said barrels, as set forth.

5. The holder consisting of two correspondingly-grooved hinged sections, clamped together to form a series of barrels for explosives, provided with a common fuse-chamber and communicating ducts, substantially as set forth.

B. JAY ANTRIM.
